UNITED STATES PATENT OFFICE.

GEORGE LINCOLN ESTES, OF OKLAHOMA CITY, OKLAHOMA.

STOP SIGNAL FOR CROSSINGS.

Application filed February 21, 1925. Serial No. 10,843.

The object of the invention is to provide a device of this character which will catch the eye quickly, be easily and plainly discernible night and day regardless of the 5 weather, strong, durable, substantially fixed on the pavement or street with minimum damage to pavement, with little likelihood of being broken or out of place when installed.

10 The use of the automobile has become so general as to make it necessary to safeguard life of persons in the public streets and by as cheap and economic a manner of handling as possible, owing to the necessity of 15 control at so many intersecting crossings.

The invention, novel features, details of construction and combination of parts, and other objects of the invention will be hereinafter more particularly set forth, illustrated in the accompanying one-page drawing and pointed out in the appended claim.

Reference to the drawing forming a part of this application,

Figure 1 is a perspective view of the device.

Figure 2 is a bottom view.

Figure 3 is a perspective sectional view.

Figure 4 is a partial perspective view.

Figure 5 is an enlarged partial section 30 view of the reflector of the device.

Like characters of reference designate like parts in all figures.

The device consists of a semi-spherically shaped body, preferably of metal, its lower portion 1 resting on the pavement or ground, the extreme outer rim being thickened 2 for a distance 3 from the pavement or ground, for strength. The angle of the periphery of said device for the same reason is the same throughout its entire surface the highest point being shown at 4. There is a plurality of holes 14 oppositely and at right angles to the signal portion 5 of the device recessed near the outer edge as shown at 14 which are re-inforced for a short distance upon the inside of said body 16, 17. The body is held in place by lag-screws 15 through apertures 14 into the pavement, or ground, and by a longer lag-screw or bolt through aperture 20 in the top. The shape of the body being semi-spherical distributes equally the shock or blow from concussion of vehicles striking the device, and from thereby breaking and injuring the 55 device.

The lag-screws being small prevent de-

struction or injury to the paving, and yet prevent the device turning or getting out of position desired for giving notice to the traveling public.

On the side of the device facing approaching vehicles and on which is desired to be placed indicia is an inclined plane surface, preferably oblong in shape 5, 6, 6, 7, 10, slanting from a point near the bottom of 60 the front of the device 5 at an angle of approximately 45° to a point near its top 10. Stop, 8, or other suitable indicia, as desired, may be used on said inclined plane surface. It is desired not to have such surface extend over one-fourth of the circumference so as if desired other inclined plane surfaces may be used for the other indicia towards directions from which streets, or highways approach the device, as shown by 70 Fig. 4, and in which event the direction to the traffic may be shown by an arrow 18 and points 19.

In the upper portion of said inclined surface is a recessed portion 11, 12 which with 80 the bossed portion 9 holds in place a prismatic ruby jewel 21 back of which is a reflector 13; the recessed portion 12 is lower at the front and outer portion of the aperture than at its inner portion 11, allowing 85 drainage, etc.

The preferred color of the body of the device is red; the preferred color of the inclined plane portion 5 is white, and the preferred color of the indicia 8 is red. When 90 used on brick paving, or when otherwise desired the device may be filled with cement and allowed to harden. When used on asphalt pavement, and when otherwise desired, the device may be used simply as a shell without the cement. When so used if preferred a ribbed reinforcing 23, 25, 26, may be used between the reinforced recessed portions 16, 17 and the reinforced inside 95 center of the device 22 surrounding the hole 100 20, and for reinforcing beneath and surrounding the ruby jewel 21 a ribbed reinforcing 24 on the inside portion of said inclined plane surface to a point near its lower 105 inner edge.

It will be seen from the angle given the inclined plane, the ruby jewel at the top thereof will be in a position to catch the rays of light from approaching automobiles producing the identical effect of appearances as an electric light would have back of such ruby jewel, and making the use of the de-

vice as complete as if connected up with electricity and light bulb.

Other indicia than Stop such as Slow, Right, Left, One way, etc., may be used.

5 From the description of the accompanying one page drawing, and the specifications the advantages of application, construction and operation will be apparent to those skilled in the art to which my invention pertains; 10 but it will be understood that any modification within scope of the claimed invention may be made in the construction without departing from the principle of the invention or sacrificing any of its advantages.

15 Having thus described the invention what

is claimed and desired to be secured by Letters Patent, is:

As an improved article of manufacture, the herein described stop signal embodying in a single element a hemi-spherical shaped 20 hollow body with interior reinforcements at the base with their bases apertured for the reception of securing means, and provided with a plane sloping surface for indicia having a side recess at the top thereof to receive a jewel, and a radial reinforcing rib extended from the inner rim of the base to said jewel-receiving recess.

GEORGE L. ESTES.
